[57] CLAIM

The ornamental design for a connector for corrugated plastic pipe, as shown and described.

DESCRIPTION

FIG. 1 is a top perspective view of a connector for corrugated plastic pipe showing my new design;

FIG. 2 is a top plan view thereof, the bottom plan view being identical;

FIG. 3 is a front elevational view thereof, the rear being the same as the front shown; and,

FIG. 4 is a left side elevational view thereof, the right side being the same as the left side.

FIG. 1.

FIG. 3.

FIG. 2.

FIG. 4.
